UNITED STATES PATENT OFFICE.

EBENEZER V. WHITE, OF GLADSTONE, MICHIGAN.

DESIGN FOR A NECKTIE-FASTENER.

SPECIFICATION forming part of Design No. 31,576, dated October 3, 1899.

Application filed June 12, 1899. Serial No. 720,308. Term of patent 14 years.

To all whom it may concern:

Be it known that I, EBENEZER V. WHITE, a citizen of the United States, residing at Gladstone, in the county of Delta and State of Michigan, have invented and produced a new and original Design for Necktie-Fasteners; and I do hereby declare the following to be a full, clear, and exact description of the invention, such as will enable others skilled in the art to which it appertains to make and use the same.

In the accompanying drawings, Figure 1 shows a side elevation of my newly-designed necktie-fastener. Fig. 2 is a perspective view of the fastener on an enlarged scale.

The essential features of the design are a downwardly-projecting pointed part, an upwardly-extending shank united therewith by an intermediate portion, and a ring at the top of the shank having its end slightly twisted out of the general plane of the ring.

The part *a*, having the point *b*, is connected at its upper end by a curve *c* with the intermediate portion *d*, which runs down to a curve

e, located just below the point *b* and underneath it to a certain extent. From the curve *e* the shank *f* rises to a point at about the same height as the curve *c* and is there formed into a ring *g*. The parts *a*, *d*, and *f* lie substantially in the same plane, while the ring is in a plane transverse thereto. The end *h* of the ring is twisted out of the general plane of the ring toward the curve *c*. When in use, the necktie is caught on the pointed part *a* and the collar is received between the parts *d* and *f*.

Having thus described my invention, what I claim, and desire to secure by Letters Patent, is—

The design for a necktie-fastener, substantially as shown and described.

In testimony whereof I affix my signature in presence of two witnesses.

EBENEZER V. WHITE.
